UNITED STATES PATENT OFFICE.

JOHN G. WILLET, OF BUFFALO, NEW YORK, ASSIGNOR OF EIGHTEEN ONE-HUNDREDTHS TO ISIDORE MICHAEL, EIGHTEEN ONE-HUNDREDTHS TO EDWARD MICHAEL, EIGHTEEN ONE-HUNDREDTHS TO CLARK L. INGHAM, AND EIGHTEEN ONE-HUNDREDTHS TO ELLGOOD C. LUFKIN, ALL OF BUFFALO, NEW YORK.

CARBURETER.

979,908.

Specification of Letters Patent. Patented Dec. 27, 1910.

Application filed February 23, 1907. Serial No. 358,852.

To all whom it may concern:

Be it known that I, JOHN G. WILLET, a citizen of the United States, residing at Buffalo, in the county of Erie and State of New York, have invented a new and useful Improvement in Carbureters, of which the following is a specification.

This invention relates to an improved carbureter for hydrocarbon or explosive engines. One of its objects is the construction of a simple carbureter of this class which maintains the proper proportion of air and gasoline or other suitable liquid hydrocarbon to produce a perfect explosive mixture at all engine speeds.

The invention has the further object to improve the construction of the carbureter with a view of rendering its parts easy of assemblage and facilitating access to them for cleaning or other purposes.

In the accompanying drawings consisting of 2 sheets: Figure 1 is a sectional elevation of the carbureter. Figs. 2, 3 and 4 are horizontal sections in the correspondingly-numbered lines in Fig. 1.

Similar letters of reference indicate corresponding parts throughout the several views.

The body or casing of the carbureter preferably consists of flanged upper and lower sections A, A¹ secured together by clamping bolts *a* passing through their flanges.

B is a float-chamber or gasoline reservoir of any suitable construction having a discharge nipple *b* which is screwed into an enlargement at the outer end of the gasoline inlet *c* of the carbureter. The chamber B contains a float D which controls the customary cut-off valve *d*.

As shown in Figs. 1 and 3, the inlet *c* is formed in one of the radial arms of a spider or bridge-piece E arranged horizontally within the lower section A¹ and preferably cast integral therewith. The inlet *c* leads to a valve chamber *f* formed in the hub of said spider and containing an adjustable needle valve *f*¹ of any suitable construction adapted to close against a conical seat at the lower end of a passage *g* formed in a head or manifold G. The stem of this valve extends through a stuffing box in the bottom of the carbureter-casing and has the usual head for turning it, as shown.

The head G has a reduced stem *g*¹ which

is screwed into the upper end of the valve-chamber *f* or otherwise removably secured in place. Connected with the bore or passage *g* are a number of gasoline pipes *h* extending radially from the head G and having upwardly-turned portions *h*¹ forming spray or vaporizing nozzles. In the drawings six of such nozzles are shown which are arranged centrally opposite the spaces between the spider arms E, but a greater or less number may be employed and they may be differently spaced, if desired.

I is the air-inlet passage or connection of the carbureter carried by its lower section A¹, and preferably connected therewith below the spider E, as shown, whereby the incoming air is broken up into numerous streams.

J indicates the mixture-outlet connected with the upper section A of the casing and controlled by a suitable throttle valve K. In the construction shown in the drawings, this valve is of the hollow rotary type, and fitted in the cylindrical neck of the carbureter, the valve being open at its lower end and closed at its upper end and provided in its side with a discharge port *k* adapted to register with the mixture outlet J. At its upper end the throttle valve is provided with a hollow stem *k*¹ which turns in an opening or bearing in the cap of the carbureter casing. To the projecting end of this stem is secured an actuating lever L adapted to be connected with the hand lever or equivalent actuating device on an automobile or motor boat.

M indicates a horizontal diaphragm or partition arranged in the casing and dividing the same into a lower inlet chamber N and an upper mixing chamber N¹ with which the air inlet connection I and the mixture outlet connection J communicate, respectively. The diaphragm, which is preferably integral with the upper section A of the casing, is provided with an annular row of air passages *m* which extend through the same and are arranged respectively coincident with the vaporizing nozzles *h*¹, which latter preferably project into the passages, as shown in Figs. 1 and 2, so that the fuel issuing from the nozzle is intimately mixed with the air ascending through the passages. These passages are always open and have such an aggregate area as to supply

the proper proportion of air to the hydrocarbon when the engine is running at ordinary or low and intermediate speeds.

As is well known, when the engine runs at high speed, the increased suction produced by the engine results in an increased aspiratory effect upon the vaporizing nozzles, causing a larger quantity of gasoline to be drawn from the nozzles and supplied to the mixing chamber N¹. In order to supply the necessary additional quantity of air to maintain a proper explosive mixture under such conditions, the diaphragm M is provided centrally with a comparatively large supplemental air port or passage o controlled by an automatic valve P which remains closed at low and medium engine speeds, but opens automatically under the influence of the increased suction of the engine when the engine runs at high speed, permitting air to enter the mixing chamber both through the main passages m and the supplemental passage o. The automatic valve is preferably conical with its apex arranged downward and closes against a corresponding seat at the upper edge of said supplemental passage. The valve slides vertically on a guide or rod p arranged centrally in the carburetor casing and made vertically adjustable in the hollow stem of the throttle valve by means of a screw threaded joint p¹, as shown, or any other suitable means. The guide-rod p is secured in position by a lock nut p² and its projecting upper end has a knurled head for turning it.

q indicates a spring applied to the guide-rod p between a fixed collar q¹ thereof and the hub of the valve P and tending to hold the valve to its seat. By adjusting the guide up or down, the tension of the spring may be regulated to offer the desired resistance to the valve. By making this valve conical and extending it above and below its seat, as shown, it serves also as a deflector which directs the air ascending through the supplementary passage o outwardly in all directions toward the mouths of the vaporizing nozzles h¹, thus bringing such additional air as well as the air drawn through the main passages m into intimate contact with the vaporized gasoline issuing from the nozzles and thoroughly and uniformly carbureting the same. Very satisfactory results have been obtained by extending the valve P some distance below the diaphragm M and making its large upper end of such diameter that the same overhangs the inner edges of the main air passages m, as shown in Figs. 1 and 2.

60 In the operation of the carburetor when the engine is running at low or medium speed, the automatic valve P remains closed and sufficient air is supplied through the main passages m to produce a proper explosive mixture under these conditions.

When however, the engine is run at a high speed, and resistance of the spring q is overcome by the increased suction of the engine and the valve P is opened more or less according to the degree of speed, supplying the necessary additional quantity of air to form a perfect explosive mixture with the increased supply of gasoline due to the greater suction. A practically constant proportion of air and gas is thus maintained regardless of the speed of the engine.

By dividing the casing of the carburetor into upper and lower sections at a point below the diaphragm M and mounting the vaporizing nozzles h¹ on the lower section, as shown, the nozzles are accessible upon removing the clamping bolts a and can be easily cleaned. This construction also permits the ready removal and replacement of the detachable head G which carries the vaporizing nozzles, without disturbing the adjustment of the needle-valve f¹.

I claim as my invention:

1. In a carburetor, the combination of a casing having fuel and air inlets, a mixture outlet, and a diaphragm which divides the casing into an inlet chamber and a mixing chamber, said diaphragm having one or more main air passages and a supplemental air passage, vaporizing nozzles arranged adjacent to said main air passages and connected with said fuel inlet, and an automatic valve normally closing said supplemental passage and controlled by the suction of the motor supplied by the carburetor, said valve having deflecting means for directing the air which flows through the supplemental passage toward said nozzles, substantially as set forth.

2. In a carburetor, the combination of a casing having fuel and air inlets, a mixture outlet, and a diaphragm which divides the casing into an inlet chamber and a mixing chamber, said diaphragm having a row of main air passages and a supplemental air passage surrounded by the row of main passages, vaporizing nozzles arranged adjacent to said main passages, and an automatic valve normally closing said supplemental air passage and having a conical deflecting face, substantially as set forth.

3. In a carburetor, the combination of a casing having fuel and air inlets, a mixture outlet, and a diaphragm which divides the casing into an inlet chamber and a mixing chamber, said diaphragm having a row of main air passages and a supplemental air passage surrounded by the row of main passages, vaporizing nozzles arranged adjacent to said main passages, and an automatic valve normally closing said supplemental passage and having a conical deflecting face which extends above and below said diaphragm, substantially as set forth.

4. In a carburetor, the combination of a

- casing having fuel and air inlets, a mixture outlet, and a diaphragm which divides the casing into an inlet chamber and a mixing chamber, said diaphragm having a row of 5 main air passages and a supplemental air passage surrounded by said row of main passages, vaporizing nozzles projecting into said main passages, and an automatic valve normally closing said supplemental passage 10 and having a conical deflecting face which extends above said diaphragm and overhangs said main passages, substantially as set forth.
5. In a carbureter, the combination of a 15 casing having fuel and air inlets, a mixture outlet, and a diaphragm which divides the casing into an inlet chamber and a mixing chamber, said diaphragm having one or more main air passages and a supplemental 20 air passage, vaporizing nozzles arranged adjacent to said main air passages and connected with said fuel inlet, a guide arranged in line with said supplemental passage and capable of longitudinal adjustment in the 25 top of the casing, a valve slidably mounted

on said guide and normally closing said supplemental passage, and a spring carried by said guide and bearing against said valve, substantially as set forth.

6. In a carbureter, the combination of a 30 casing having air and fuel inlets, a mixture outlet and a diaphragm dividing the casing into an inlet and a mixing chamber, said diaphragm having a central air passage and a plurality of outer passages arranged 35 around the central passage and open at all times, a plurality of vaporizing nozzles arranged adjacent to said outer passages, respectively, and connected with said fuel inlet, and an automatic valve normally closing 40 said central passage and controlled by the suction of the motor supplied by the carbureter, substantially as set forth.

Witness my hand this 20th day of February, 1907.

JOHN G. WILLET.
